ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEATING DEVICE

Application filed December 24, 1928. Serial No. 328,078.

My invention relates to heating devices and more particularly to devices comprising a radiator unit, connected with a steam feed line wherein the steam before admission to the radiator unit, is utilized to actuate a turbine which drives a fan so positioned as to force a column of air between the radiator tubes and thereby accelerate radiation.

Another object is the provision of improved means for draining off the water resulting from condensation of the steam in the turbine casing, the water being discharged into the outlet end of the radiator unit without the possibility of any back flow or return of steam in the direction of the main feed pipe.

Still another object is the provision of a device that is simple, compact, efficient and satisfactory.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a plan view of one embodiment of my invention;

Fig. 2 is an elevational view of the same;

Fig. 3 is a view along the line 3—3 of Fig. 2;

Fig. 4 is a view along the line 4—4 of Fig. 1;

Fig. 5 is a view along the line 5—5 of Fig. 1; and

Fig. 6 is a view along the line 6—6 of Fig. 1.

Referring now to the drawings, the numeral 10 generally designates a radiator unit having header tanks 11 and 12. The radiator unit 10 is positioned horizontally and comprises a plurality of tubes 13 separated by a plurality of transversely extending fins or plates 14. The radiator unit 10 is shown as suspended from a steam supply pipe 17 which is connected with a generally circular-shaped

member 20 by means of a nipple 19 and a union 18. The nipple 19 has a threaded connection with an elongated casing 21 which forms an inlet chamber 15 into which steam is discharged from the supply line 17 through the nipple 19. 55

An irregular annular-shaped casing 22 is positioned immediately underneath the member 20 and is fastened thereto by a plurality of bolts 32. A turbine wheel 23 is shown as mounted in the casing 22, upon a vertical shaft 25. The chamber 15 is connected with the turbine casing 22 by a duct 27 in which a nozzle 28 is mounted. The nozzle 28 is so positioned as to discharge the steam from the chamber as a jet which impinges against the vanes of the turbine wheel 23. The resulting rotation of the wheel 23 and the shaft 25, actuates a fan 24 which is mounted on the lower end of the shaft. 60 65 70

The steam, after performing work upon the turbine wheel 23, leaves the casing 22 and enters a conduit 35 from the lower end of which it is discharged into the header tank 11. From the header tank 11 the steam is distributed through the tubes 13 in which it loses its heat to the air currents which are set in motion by the fan 24 and enters the header tank 12 from which the steam is discharged through a return pipe 33. It is 75 80 85 obvious that the steam, in travelling through the device, performs the dual function of doing work by actuating the turbine wheel 23 and the fan 24 which is connected therewith, and of discharging its energy in the form of radiated heat given off by the radiator tubes 13.

The vertical shaft 25 is enclosed in a housing 26 which is positioned in the path of the air currents induced by the rotation of the fan 24. 90

The nozzle 28 is adjustably mounted in the duct 27 by means of a set screw 29 as is best shown in the sectional view indicated at Fig. 95 6. A threaded plug 30 provides means for access to the nozzle 28 for adjustment or cleaning of the same. If necessary, the entire housing 26, in which the duct 27 is located can be removed by loosening the bolts 40 100

which are used for fastening the housing 48 to the plate member 20.

Such of the steam as is condensed in the chamber 15 collects at the bottom of the conduit 36. A shoulder 41 prevents any of this 5 condensed steam from flowing into the turbine wheel 23 through the duct 27.

A float valve generally designated 34 is suitably positioned in the bottom of the conduit 36 to permit the discharge of surplus 10 water from the conduit 36 into the header tank 12. A water seal is also provided which prevents any possibility of back flow of steam from the header tank 12. The float valve 15 preferably takes the form of a vertical cylinder 49 having end pin bearings 42. A plug 46 provides a means of access to the float 20 valve 34. A hollow inverted L-shaped member 43, mounted in the bottom of the conduit 36 provides an outlet for the surplus water 25 and also functions to retain sufficient water in the conduit 36 to form a water seal. A port 44 in the plug 46 and a similar port 45 in the L-shaped member 43 provide mountings 30 for the pin bearings 42. As the water level 35 in the conduit 36 rises the cylinder 49 is elevated and thereby permits water to flow through the port 45 and into and through the member 43 from which it is discharged into 40 the header tank 12. As the water recedes the cylinder 49 drops and closes the port 45. The port 45 is vertical with its lower end submerged in the water which surrounds the downwardly projecting free end of the member 43. The water thus retained in the conduit 36 provides a water seal preventing any 45 back flow of steam from the header tank 12, through the member 43.

The radiator unit 10 is fastened to the conduits 35 and 36 by the bolts 37 and 38, respectively. The conduit 35 is fastened to the member 20 by bolts 39 and the conduit 36 is similarly fastened by bolts 40. The various members comprising the device being bolted 45 together are easily assembled and disassembled and can be readily mounted in any suitable steam line.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In apparatus of the kind described, a radiator unit, a steam supply pipe, a turbine casing into which said pipe discharges, a conduit connecting said casing with the inlet end of the radiator unit, a second conduit connecting said casing with the outlet end of the radiator unit, and float valve means in said second conduit automatically

operable to intermittently discharge water from the conduit into the outlet end of the radiator unit.

2. In apparatus of the kind described, a radiator unit, a steam supply pipe, a turbine 70 casing into which said pipe discharges, a conduit connecting said casing with the inlet end of the radiator unit, a second conduit connecting said casing with the outlet end 75 of the radiator unit, float valve means in said second conduit automatically operable to intermittently discharge water from the conduit into the outlet end of the radiator unit, and a return pipe into which said radiator 80 unit discharges.

3. In apparatus of the kind described, a radiator unit, a steam supply pipe, a turbine casing into which said pipe discharges, a conduit connecting said casing with the inlet end of the radiator unit, a second conduit connecting said casing with the outlet end of the radiator unit, float controlled means in 85 said second conduit automatically operable to intermittently discharge water from the conduit into the outlet end of the radiator 90 unit, a turbine wheel in said casing, and a fan positioned adjacent said device and operatively connected with said wheel.

4. In apparatus of the kind described, a radiator unit, a steam supply pipe, a turbine 95 casing into which said pipe discharges, a turbine wheel in said casing, a fan positioned adjacent said device and operatively connected with said wheel, said turbine casing being positioned in the path of air currents 100 induced by the rotation of the fan, a conduit connecting said casing with the inlet end of the radiator unit, a second conduit connecting said casing with the outlet end of the radiator unit, and float valve means in said 105 second conduit automatically operable to intermittently discharge water from the conduit into the outlet end of the radiator unit.

5. In apparatus of the kind described, a 110 casing providing a steam inlet chamber, a steam supply pipe discharging into said chamber, a turbine casing, a turbine wheel mounted in the turbine casing, a nozzle connecting said casings, said nozzle being positioned to direct a steam jet on said wheel, a radiator unit, a conduit connecting the turbine casing with the inlet end of the radiator unit, a pipe connecting said chamber with the outlet end of the radiator unit, and float valve mechanism in said pipe operable to intermittently discharge water from the pipe into the radiator unit.

6. In apparatus of the kind described, a 115 casing providing a steam inlet chamber, a steam supply pipe discharging into said chamber, a turbine casing, a turbine wheel mounted in the turbine casing, a nozzle connecting said casings, said nozzle being positioned to direct a steam jet on said wheel, a radiator unit, a conduit connecting the tur-

- bine casing with the inlet end of the radiator unit, a hollow L-shaped member connecting said pipe with the outlet end of the radiator unit forming a water seal, and float valve mechanism operable to intermittently discharge water through said L-shaped member. 5
7. In apparatus of the kind described, a radiator unit, a steam supply pipe, a turbine casing into which said pipe discharges, a turbine wheel in said casing, and a fan positioned adjacent said device and operatively connected with said wheel, and elements connected with the opposite ends of the radiator unit and extending between said unit and said casing, one of said elements providing a passage for steam and both of said elements providing supports for supporting said radiator unit relatively to said casing. 10
8. In apparatus of the kind described, the combination of a turbine casing, a turbine wheel located therein, a pipe for supplying steam to said turbine casing, a radiator, pipe connections extending from the turbine casing, said pipe connections being connected to the opposite ends of said radiator, and a fan located between the radiator and casing. 15
9. In apparatus of the kind described, the combination of a turbine casing, a turbine wheel located therein, a pipe for supplying steam to said turbine casing, a radiator, pipe connections extending from the turbine casing, said pipe connections being connected to the opposite ends of said radiator, and a fan located between the radiator and casing, one of said pipe connections having a valve. 20
10. In apparatus of the kind described, the combination of a turbine casing, a turbine wheel located in the casing, a steam supply for said casing, a radiator, a pipe connected at one end with said turbine casing and having the opposite end connected with one end of said radiator and providing means for supporting said radiator from said casing, and a fan connected with the turbine, said fan being located between said radiator and turbine casing. 25
11. In apparatus of the kind described, the combination of a member providing a steam passage, a casing, a turbine located in said casing, means providing a communication between said passage and turbine casing, a fan connected with said turbine, a radiator, and pipe connections respectively connected with said steam passage and turbine casing, one of said pipe connections providing means for supplying steam to said radiator. 30
12. In apparatus of the kind described, the combination of a member providing a steam passage, a casing, a turbine located in said casing, means providing a communication between said passage and turbine casing, a fan connected with said turbine, a radiator, and pipe connections respectively connected with said steam passage and turbine casing, 35
- one of said pipe connections providing means for supplying steam to said radiator, the other pipe connection having a valve located therein. 40
13. A heating unit comprised of a radiator, a fan, and a member providing a support for said radiator and fan and providing means through which a heating medium is supplied to said radiator, elements extending from said member, said elements being connected with said radiator to maintain said radiator in spaced relation to said member, one of said elements providing means through which said medium is supplied to said radiator, said fan being arranged to rotate in a plane parallel with the plane of said radiator and said radiator being arranged in a plane transverse to the axis of said member. 45
- In testimony whereof, I have hereunto signed my name. 50
